[57] CLAIM

The ornamental design for a desk top file, as shown and described.

DESCRIPTION

FIG. 1 is a perspective view of a desk top file showing my new design, a corner portion of the uppermost divider being omitted for convenience of illustration; FIG. 2 is a bottom rear perspective view thereof with the divider corner restored;

FIG. 3 is a reduced scale top plan view thereof;

FIG. 4 is a right side elevational view thereof with a portion of the side panel broken away; and

FIG. 5 is a bottom plan view thereof.
